corporation of DelawareApplication December 12, 1936, Serial No. 115,487
In Great Britain December 27, 1935

6 Claims. (Cl. 179—171)

This invention relates to carrier wave modulator arrangements and more particularly, though not exclusively, to modulator arrangements capable of being employed to modulate the amplitude 5 of a high frequency carrier in accordance with television or like signals.

There are many known methods of modulation, but when these methods are employed to secure modulation of the amplitude of a high frequency carrier in accordance with television or similar signals, serious practical difficulties are encountered. A modern high fidelity television system may involve modulation frequencies ranging from about 25 cycles per second to about 15 megacycles per second, and the modulation voltage normally available is not very great. As will readily be appreciated such a very wide range of modulation frequencies involves serious practical difficulties and the main requirements, namely the 20 achieving of as nearly as possible rectilinear modulation over the whole frequency range without requiring the modulation source to supply any appreciable amount of power, are very difficult to satisfy. As will be seen later the present invention 25 provides improved modulation systems in which these requirements are to a large extent satisfied.

According to this invention there is employed a carrier frequency amplifier whose gain is automatically controlled in dependence upon the output from said amplifier in such manner that in the absence of modulating potentials the output from said amplifier is maintained at a predetermined value, and gain control in dependence 35 upon modulation potentials is superimposed upon the gain control in dependence upon output in such manner that the output carrier frequency amplitude varies substantially rectilinearly with the modulation input.

40 The invention is illustrated in the accompanying drawing which shows in block diagram form a preferred way of carrying out the said invention.

Referring to the drawing the carrier frequency 45 to be modulated is applied from a source not shown across an input impedance 1 of any suitable nature which is included in the grid circuit of the first tube 2 of a carrier frequency amplifier represented by a rectangle 3 and which may 50 consist of the said tube only or of any desired number of tubes in cascade. The cathode or cathodes of the tube or tubes in the carrier frequency amplifier 3 is or are earthed. The output circuit of the last tube 4 in the carrier 55 frequency amplifier 3 (this tube will, of course,

be the tube 2 if the amplifier 3 contains only one tube) includes an output impedance 5, e. g., a resistance, which is earthed at the end remote from the anode. Carrier frequency voltage set up across impedance 5 is applied through a suitable condenser 6 to the anode 7 of a diode 8 whose cathode 9 is earthed through a cathode impedance 10—for example a resistance—in series with a battery 11 or suitable fixed direct current potential source, the negative terminal 10 of the said source being connected to earth and the positive terminal being connected to that end of the cathode impedance 10 remote from the cathode 9. The diode anode 7 is connected through a suitable filter 12 to that end of the 15 input impedance 1 remote from the control grid of the first tube 2 of the amplifier 3. Modulating potentials from a source not shown are applied between the diode cathode 9 and earth.

With the above described arrangement, it will 20 be seen that the first tube 2 of the carrier frequency amplifier 3 will receive gain controlling potential from the diode rectifier circuit. The arrangement is such that in the absence of modulating potentials, the voltage built up across the 25 output impedance 5 is greater than the voltage between the diode cathode 9 and earth by an amount such as will result in a negative gain controlling potential of sufficient magnitude to reduce the gain of the carrier frequency amplifier 30 3 to rather less than half its maximum value. If now, modulating potentials are superimposed between the diode cathode 9 and earth, the gain control potential applied at any instance will 35 depend upon the modulation input, and by suitably selecting the parameters of the circuit it is possible to obtain a substantially rectilinear modulation action up to a high percentage of modulation.

The invention is, of course, not limited to the 40 application of gain controlling potential to the grid of only the first tube 2 of the carrier frequency amplifier, for, if desired, more than one tube of this amplifier may be controlled as to its gain in the manner described. Again the 45 output energy taken from the amplifier for gain controlling purposes need not be taken in the manner described; for example, it may be taken by inductive coupling or even by taking up radiation from an aerial system energized by the 50 transmitter of which the carrier frequency amplifier forms part. An advantage of taking the said output energy in the last described manner, i. e., by radiation from an aerial system is that by resorting to this expedient it is possible 55

to correct automatically for any frequency distortion in the transmitter—including any due to the aerial. The diode 8 may be replaced by any suitable type of detector, e. g., a multi-grid tube, the output from which is a function of the difference between the peak or mean or root mean square value of the carrier wave and the instantaneous value of the modulating potentials, the said output being utilized to control the gain 10 of the carrier frequency amplifier.

It is found that with modulation systems in accordance with this invention, satisfactory operation over a very wide band of modulating frequencies may be obtained; rectilinear or closely 15 approximately rectilinear modulation may be obtained over substantially the whole of a wide band of modulating frequencies; quite "deep" modulation up to a high percentage of modulation may be obtained; the modulating potentials required are relatively small; substantially no power is required for modulation, i. e., the source 20 of modulating potentials is substantially unloaded; and all the tube cathodes can be earthed—an important matter from the point of view of stray capacity effects when high modulating frequencies are in question.

I claim:

1. In a carrier wave modulation system suitable 30 for modulating the amplitude of a high frequency carrier wave in accordance with television or like signals, a high frequency amplifier tube having input and output electrodes connected in input and output circuits respectively, means for applying carrier wave energy to be modulated to the input circuit of said amplifier tube, a direct 35 current impedance connected between the output electrodes of said amplifier tube, a rectifier tube having an anode and a cathode, a series circuit including a resistance coupling the anode and cathode of said rectifier tube in shunt to said 40 impedance whereby wave energy from said amplifier output is impressed on said rectifier, a control circuit connected in shunt to a portion of said series circuit, a coupling between said control circuit and an electrode in said amplifier tube 45 for applying gain controlling potentials to said electrode of said amplifier tube, and means for impressing modulating potentials on said rectifier tube to control the gain of said amplifier tube in

accordance with modulating potentials and potentials characteristic of modulated carrier energy supplied to said control circuit by said rectifier, the relative values of said first impedance and said resistance and the impedance of said 5 rectifier tube being such that in the absence of modulating potentials the gain of said amplifier tube is adjusted to approximately one-half its maximum value so that the effect of the superimposed modulating potentials and rectified potentials characteristic of the modulated carrier 10 energy is to vary the gain of said amplifier substantially rectilinearly about said adjusted value.

2. An arrangement as recited in claim 1 wherein in the control circuit is coupled to the electrode 15 in said amplifier tube by means of a filter for suppressing wave energy of a frequency of the order of the frequency of the carrier wave energy.

3. An arrangement as recited in claim 1 wherein in said electrode in said amplifier to which said control potentials are impressed is an input electrode.

4. A wave relaying tube having input electrodes on which wave energy to be modulated is impressed and having output electrodes from which 25 modulated wave energy is derived, a first impedance connected with said output electrodes, a rectifier impedance and a source of potentials and a second impedance in series in shunt to said first impedance, the polarity of said source being 30 such as to aid the potential produced in said second impedance by rectified wave energy from the output of said relaying tube, a gain control circuit connecting said rectifier to an electrode in said relaying tube, and means for impressing 35 modulating potentials on said rectifier.

5. A system as recited in claim 4 wherein said first impedance is of such a value relative to the value of said second impedance that the potential drop produced in said first impedance by 40 the output of said relaying tube in the absence of said modulating potentials is sufficient to produce a negative gain control potential in said gain control circuit.

6. A system as recited in claim 4 wherein said gain control circuit includes a filter for energy of a frequency of the order of the frequency of the wave energy to be modulated.
